COMBINATION INFLOW CONTROL AND
FLUID DISCHARGE MEANS

Marvin S. Young, Scarsdale, N. Y., assignor to
The Gas and Oil Lock Corporation, New York,
N. Y., a corporation of New York

Application September 23, 1932, Serial No. 634,498
In Canada September 23, 1931

11 Claims. (Cl. 221—28)

This invention relates to the control of liquids and more particularly relates to the system for controlling the inflow of liquids into conduits or other receptacles whereby a continuous protection and prevention of substitution can be had from the initial manufacturing source to the final consumer.

A system of controlling the dispensing of liquids, particularly gasoline and oil, has been found desirable because of the persistent substitution of inferior products of one manufacturer for those of another for which premiums were oftentimes paid without an assurance of receiving the desired product. Other substitution of inferior grades of lubricating oil, for example, of crank case drainings for first grade new oil, has taken place in many places and in my invention I have contemplated the protection of the lubricating oil or gasoline or other liquid products from the original source on down to the final retail dispensing unit. For the most part the inflow control means for the underground storage tank or tank wagon differs only in size from the inflow control means for the final retail drum, although in some cases it may be found desirable to substitute slightly different forms of valves for more viscous fluids such as oils for the control valve for gasoline and other less viscous liquids.

In connection with the protection of the dispensing system it is to be understood that practical features of rapid filling are essential and dispensing stations are periodically inspected by representatives of the producing companies. Therefore, it is only necessary to protect the container against rapid filling and prevent the ready opening of the valve as any flagrant violation will be instantly observable.

It is also to be understood that it is common to have particular routes for drivers so that each driver will fill a certain group of tanks, which routes are usually keyed or given a code number. With my invention it is possible to supply a standard key which may be changed to fit the inflow control on any particular route and without the code number the inadvertent possession of a key nozzle by an unscrupulous person would be of no avail as the key nozzle could not be changed to fit the particular inflow control on the route without knowing its code relation.

The principal object of my invention is to provide a variable key nozzle for an inflow control for controlling the inflow to a conduit or other container whereby the key may be varied in accordance with the pre-arranged lock of the

inflow control valve and will have in all other respects a standard construction for a plurality of locks.

Another object of my invention is to provide a key for a plurality of locks, each of which may have a different combination and in which the key has variable eight members which can be changed as desired to fit any of the locks.

Another object of my invention is to provide an improved inflow control valve and key nozzle for a container, more particularly adapted to receive viscous liquids such as lubricating oils, which control will permit the rapid filling of the container and which will be positively sealed when the key nozzle is removed.

Another object of my invention is to provide an improved inflow control for a conduit or other container which is more particularly adapted to receive less viscous liquids such as gasoline, water, etc., and which is normally adapted to receive large quantities of fluid.

A further object of the invention is to reduce the overall diameter of inflow control heads with respect to the available internal fluid conduit bore by positioning the lock tumblers in an axis parallel to the axis of flow and thereby reducing their overall interference with flow.

Further objects and advantages of my invention will appear from the following description thereof taken in connection with the attached drawings which illustrate certain preferred forms of embodiment, and in which:

Figure 1 is an elevation, partly in section, showing the retail dispensing unit;

Figure 2 is a vertical section taken substantially on the line 2—2 of Figure 1 showing the drum inflow control;

Figure 3 is a horizontal section on the line 3—3 of Figure 2 showing the inner details of the drum inflow control;

Figure 4 is a horizontal section similar to that of Figure 3 with the inflow control valve open;

Figure 5 is an elevation of a conduit inflow control with parts in section;

Figure 6 is a vertical section of the inflow control of Figure 5, taken at 90° to Figure 5;

Figures 7, 8 and 9 are horizontal sections taken respectively on the lines 7—7, 8—8 and 9—9 on Figures 5 and 6;

Figure 10 is a side elevation of a modified form of conduit inflow control and key nozzle, with parts in section;

Figure 11 is a perspective view of a key;

Figure 12 is a side elevation of the key in place, and,

Figure 13 is a partial bottom plan view showing the code relation of the keys.

The retail dispensing unit shown in Figure 1 comprises a container such as a drum 10 fitted 5 with a suitable inflow control valve 12 having a suitable dust proof cap 11 through which fluids are introduced into the container. The inflow controlling device 12 is sealed into the drum in any desired manner such as by the projecting lug 13 which engages under the top of the container and in lug 15a cooperates with the spring member 15. The liquids may be suitably removed through a pump 14 which discharges through a discharge control 16 into a receptacle such as a unit measure 18 having the receptacle top 20 and inflow control nozzle integral therewith. A measuring stick 19 can be used to determine the volume of remaining fluid.

One form of combination inflow controlling 20 and fluid discharge means 16 and 20 is generally described in my prior Patent No. 1,682,544, issued August 28, 1928, and by such construction the purchaser of the unit quantity carried in the measure 18 can be assured of obtaining liquids dispensed from the drum 10, the filling of which 25 may also be controlled by the producing company.

As a further step in the protection of the system, the liquids placed within the container 30 10 are also under control and the drum is sealed against filling except through the inflow control valve 12 having a cooperating key nozzle 26 which is in turn carried by an authorized filling operator. The key nozzle may preferably have, 35 in one form, as shown for example in Figure 2, a projecting key member 29 which cooperates with the tumblers 28 normally projecting from a relatively rotatable valve part 27. The relatively rotatable valve part 27 cooperates with the semi-cylindrical housing 25 of the inflow control valve 12 to normally seal the opening in 40 the top of the drum 10. As shown in Figure 3, the bottom of the relatively rotatable part 27 covers the other half of the bottom formed by semi-circular extension 25a of the inflow control housing 25 so that under normal conditions 45 it is substantially impossible to introduce fluids into the drum. The key nozzle 26 may preferably be of short length and funnel shaped at the open end so that it may be used to assist 50 pouring of liquids to fill the drum 10.

The tumblers 28 project from the fixed housing 25 into the rotatable part of the housing 27, and as is commonly known with tumbler locks, the parting lines 24 are at irregular intervals 55 so that the rotatable part of the housing cannot be rotated. If, however, the correct key 29 is placed into alignment with the projecting tumblers 28, the parting lines 24 will be in proper position so that the rotatable part of the housing 60 27 may be relatively rotated about the bottom pivot 21. Under such conditions the bottom is then half opened as shown in Figure 4 inasmuch as the key nozzle 26 can be manipulated to rotate the rotatable half of the housing 25, 65 thus opening the bottom. The angular projection 23 on the key nozzle 26 cooperates with the projection portion surrounding the tumblers on the rotatable part of the housing 27 to accomplish this result.

The key nozzle 26 is preferably arranged so that it cannot be removed from the rotatable part of the housing 27 while the inflow control is in the open position. One method of 70 insuring this result is to construct the key 29

so that the lower most eight portions will not pass the projections of the other tumblers when held in the extended position. It will therefore be necessary to return the key nozzle 26 to its closed position before it may be removed. Other 5 arrangements for this purpose will be evident.

As the rotatable and fixed parts of the valve 10 casing fit rather close, it would normally be impractical to fill a container with a viscous liquid such as oil as the slow rate with which the oil would flow would invite detection. Furthermore, the key nozzle 26 being of funnel shape, is readily adapted to receive large quantities of a viscous liquid and has ample capacity to fill the drum 10 in a manner satisfactory in commercial practice.

Where liquids such as gasoline and similar less viscous liquids are handled, and such liquids are normally conveyed through a hose or pipe, the modified inflow construction shown in Figures 5 to 9 may be preferred. The inflow conduit or neck of a container 30 is adapted to receive the inflow control means 32 which may be screwed into the pipe or neck and retained in any permanent manner. The inflow control 25 more particularly shown in Figure 5 further includes a key nozzle 34 preferably carried on the end of a conveying hose or pipe 36 and secured thereto by a coupling 38. It is of course to be understood that the conduit 36 might be a fixed 30 as well as a flexible pipe as is similarly true of the inflow conduit 38. A suitable coupling 39 will hold the key nozzle 34 in firm contact in the control head 32.

A valve 40 of any desired type, such as a centrally pivoted and balanced flap valve may effectively be used and is mounted in a central sleeve 42 which is non-rotatably held by the set screw 42a. The valve is held closed by a relatively rotatable sleeve 43 having a cam surface 49. The valve may economically be made of one piece construction and where pivoted in the center, can be easily and positively closed. The relatively rotatable sleeve 43 is held in a fixed position by longitudinally projecting tumblers 44 45 which cooperate in turn with the key 45 on the peripheral edge of the key nozzle 34. As the key 45 cooperates with the end of the tumblers 44 forcing them into a new position, a reduced section of the tumblers 44a passes a projecting portion 47 in the fixed intermediate sleeve 42 as more particularly shown in Figure 9.

Inasmuch as the reduced section 44a of the tumblers 44 will allow the rotatable sleeve 43 to pass the tumblers and therefore move relatively 55 to the fixed sleeve 42 the cam surface 49 will rotate the butterfly valve 40. The angle of the cam is preferably such that but one-quarter to one-eighth of a turn is sufficient to cause this opening.

An L-shaped slot 42b may be cut in the inner sleeve 42 to cooperate with a projection 34a on the nozzle 34 so that in partial rotation of the key nozzle, the slot will hold the nozzle from being removed. It is therefore necessary to close the valve 40 if the nozzle is to be removed. It is to be understood that the tumblers 44 may be of any number such as four or more or less and that the reduced portions 44a may be varied in position in accordance with the usual tumbler lock combinations. The key likewise will have corresponding shoulders 45 formed either as slots or as additional projections extending from the peripheral surface of the key nozzle 34.

When the tumblers are placed in a longi- 75

tudinal position or in other words, when they are parallel to the axis of flow in the conduits, the least space in the line of flow is occupied. The key, also being substantially on the peripheral edge of the nozzle, the remaining part of the conduit is free to the passage of fluids. Therefore, the present construction greatly reduces the necessary overall size of inflow control head corresponding to a fixed size of bore 10 and gives full free flow.

The valve will effectively prevent flow of liquids into the filling pipe 30 except when the particular key nozzle 34 is projected into the valve control head 32, and the butterfly valve 15 opened, and yet it may be opened quickly and easily.

A modified form of construction in which the key of the nozzle can be changed is shown in Figures 10 to 13 inclusive. The inflow control 20 element 50 is adapted to be mounted in a suitable conduit on a container as desired and is provided with a similar pivoted or other valve 52 which is controlled by the relative rotation of the inner sleeve 54 with respect to the inflow 25 control head 50. As previously disclosed, a series of tumblers 56 are preferably mounted within the control head 50 and cooperate with the rotatable sleeve in such manner that when properly depressed a relative rotation may be had 30 between the rotatable sleeve 54 and the inflow control head 50. The key nozzle 57 is adapted to be attached to a hose of any desired form and has a collar 58 which will bring the key elements 59 into co-action with the tumblers 56. 35 The key elements 59 are more clearly shown in Figure 11 and are provided with multiple surfaces 60, 61, 62 and 63, which are of different height and one of which will cooperate with the adjacent tumbler when in position. A shank 40 64 cooperates with a suitable aperture in the guide 65 which is a part of the key nozzle 57 to hold the tumbler in the proper position and a spring 66 cooperates with each key 59 to hold it in the position in which it is set.

45 Each of the key elements 59 can be partially displaced and rotated to a sufficient extent to bring a different height surface into contact with the tumbler with which it cooperates. The different heights will therefore change the distance to which the tumblers 56 are displaced when the key nozzle 57 is in proper position and will therefore cooperate with a changed combination of tumblers. As each key may have two or more lands or height surfaces and as each 50 key can be changed for the different height without structural changes it is therefore possible to adapt one key nozzle 57 to a very great range of flow control heads having the cooperating lock relation.

60 To facilitate setting of the key each key element is provided with a number corresponding to a different height and as more particularly shown in Figure 13 the keys are set in a certain relation which in the direction laid out reads the code 3-2-1-4. If any of these keys are 65 changed it will immediately prevent the operation of the key nozzle in the head in which the tumblers are set for the corresponding code number 3-2-1-4.

70 In practice each inflow control head will have a particular code number, or, for example, all of the control heads on a single route may have the same number. Therefore, if the number is known, the operator can adjust his key nozzle to cooperate with the control heads on his route

and if the driver should desire to open the control heads on a different route he would merely have to change the relation of the key in the nozzle in accordance with the code number of the inflow control head of that particular installation. The inadvertent possession of the key nozzle would be of little avail to anyone else, however, as such person would not know the code number of the inflow control heads in any particular location and would therefore be 10 unable to set the keys in the proper combination arrangement.

Such a construction is of particular value where drivers for relief purposes may operate over a great number of different routes or be required to open the control heads having a number of different combinations. It is also available for other purposes wherever a series of locks have a specific tumbler relation which may be reduced to a code and where the key may be 20 temporarily changed to cooperate with each lock as desired.

It is equally as possible to use such a construction with the removable key nozzle as shown in Figure 2 in which it is merely necessary to 25 change the particular key for the adjustable type of key as shown in Figure 10. It is also to be noted that while the vertical or longitudinal type of plunger more particularly shown in Figures 5 to 13 is preferred it is possible to substitute in the pivoted flap valve construction the transverse type of plunger as shown in Figure 2, and of course, although the small inflow control head indicated on the drawings is of relatively less diameter than the inflow control head shown 30 in Figure 2, this is merely a matter of degree and either type of head might be made of any diameter found desirable. The constructions shown are preferably of small diameter such as three inches for the non-viscous control head 35 and approximately seven inches for the viscous control head, as these are adapted to cooperate with the common type of hose and other present day commercial equipment. This, however, is not a limitative feature and should not be so 40 construed.

While I have shown preferred forms of embodiment of my device, I am aware that other modifications may be made and I therefore desire a broad interpretation of my invention, 50 within the scope and spirit of the description herein and of the claims appended hereinafter.

I claim:

1. In combination with a receptacle, a fluid receiving conduit adapted to receive viscous liquids from a funnel shaped fluid discharge conduit having a key nozzle thereon, an inflow control head on said fluid receiving conduit, said control head including a fixed semi-cylindrical shell portion, a movable valve in said control head, said valve being complementary to said fixed shell portion, a plurality of locking tumblers projecting through the valve and fixed shell portion and holding said valve locked, said key nozzle being adapted to cooperate with said tumblers to release the locked valve.

2. A filling control for viscous liquids comprising an inflow control element, a semi-cylindrical shell with a partially closed end in said element, a relatively movable member having a 70 complementary semi-cylindrical shell with a partially closed end substantially sealing said opening, tumblers normally preventing the relative movement of the relatively movable member but adapted to be actuated to release said member, 75

and means to lock said filling control to the receiving opening of a receptacle.

3. A filling control for viscous liquids comprising an inflow control element, a semi-cylindrical bottom in said element, a relatively movable member having a complementary semi-cylindrical bottom substantially sealing said opening, tumblers normally preventing the relative movement of the relatively movable member, said tumblers projecting into a position whereby they may be moved by the insertion of a funnel shaped key into a releasing position and whereby said relatively movable member may be rotated to open part of said inflow control element for inflow of fluid, and means to prevent the removal of said key while said relatively movable member is in the open position.

4. An inflow control and fluid discharge means for fluid receivers which comprises an inflow control head sealing the fluid receiver against inflow of fluid, a rotatable valve member in said control head pivoted for rotation with respect thereto, a plurality of locking tumblers projecting across the path of rotation of the rotatable valve member and normally locking said valve member in closed position, said tumblers projecting into the path of the fluid discharge means whereby upon insertion of the cooperating fluid discharge means, the rotatable valve member may be moved into fluid inflow relation.

5. An inflow control and fluid discharge means for fluid receivers which comprises an inflow control head, means to secure said control head in a fluid tight manner to a fluid receptacle, a rotatable valve member in said control head, said control head having a semi-cylindrical fixed portion, said rotatable valve member having a cooperating complementary shape and adapted to telescope with respect to said fixed portion to open said valve to flow and means to lock said rotatable valve member in closed position to seal the fluid receptacle against inflow of liquid, said locking means including a plurality of locking tumblers projecting across the path of movement of portions of the fixed portion of the control head and a portion of the rotatable valve member, said tumblers projecting into a position whereby the insertion of a cooperating fluid discharge means will engage said tumblers and move them to inoperable position, so that the fluid discharge means can be used to rotate the valve member into a fluid inflow relation.

6. In combination with a receptacle, a fluid receiving conduit adapted to receive viscous liquids from a fluid discharge conduit having a key nozzle thereon, an inflow control head on said fluid receiving conduit, said inflow control head including a fixed cylindrically shaped shell portion having a member fixedly secured thereto and bridging said conduit, a movable valve in said control head and connected with said member, a movable cylindrically shaped shell portion, means whereby the movement of the last mentioned shell portion opens and closes said valve to establish and shut off communication through the conduit with the interior of the receptacle, and locking means normally connecting said movable shell portion with said fixed shell portion to maintain the valve in its conduit clos-

ing position but movable by said key nozzle to free said movable shell portion for movement to open said valve.

7. In combination with a receptacle, a fluid receiving conduit adapted to receive liquids from a fluid discharge conduit having a key nozzle thereon, and an inflow control head on said fluid receiving conduit, said control head comprising a valve pivoted within said conduit, a rotatable sleeve having means to hold said valve in closed position across the conduit and means to move the same positively to an open position allowing communication with the receptacle when the sleeve is rotated, and releasable means normally locking said sleeve in valve closing position but movable by said key nozzle to allow rotation of the sleeve.

8. In combination with a receptacle, a fluid receiving conduit adapted to receive liquids from a fluid discharge conduit having a key nozzle thereon, and an inflow control head on said fluid receiving conduit, said control head comprising a valve pivoted within said conduit, a rotatable sleeve having means to hold said valve in closed position across the conduit and means to move the same positively to an open position allowing communication with the receptacle when the sleeve is rotated and tumblers extending longitudinally of said conduit and normally locking said sleeve in valve closing position but movable by said key nozzle to allow rotation of the sleeve.

9. In combination with a receptacle, a fluid receiving conduit adapted to receive viscous liquids from a fluid discharge conduit having a key nozzle thereon, an inflow control head on said fluid receiving conduit, a locked valve in said control head, and a plurality of locking tumblers longitudinally arranged adjacent the edge of said conduit holding said valve locked, said tumblers being adapted to cooperate with said key nozzle whereby the valve may be unlocked.

10. In combination with a receptacle, a fluid receiving conduit adapted to receive viscous liquids from a fluid discharge conduit having a key nozzle thereon, said fluid receiving conduit comprising an inflow control head, a normally closed valve therein, an internally rotatable sleeve preventing the opening of said valve, longitudinally arranged tumbler means preventing the relative movement of said sleeve and means on said tumbler adapted to cooperate with said key nozzle to release the relatively movable sleeve whereby said valve may be opened.

11. In combination with a receptacle, a fluid receiving conduit adapted to receive viscous liquids from a fluid discharge conduit having a key nozzle thereon, an inflow control head on said fluid receiving conduit, a centrally pivoted balanced valve in said control head and means normally to hold said valve in locked position including a plurality of locking tumblers longitudinally arranged adjacent the edge of said conduit, said key nozzle adapted to cooperate with said tumbler means to release the locked valve.

MARVIN S. YOUNG.
